[57] CLAIM

The ornamental design for a coordinate measuring machine, as shown and described.

DESCRIPTION

FIG. 1 is a perspective view of a coordinate measuring machine of the claimed design;

FIG. 2 is a top plan view of the coordinate measuring machine of FIG. 1;

FIG. 3 is a front elevational view of the coordinate measuring machine of FIG. 1;

FIG. 4 is a right side elevational view of the coordinate measuring machine of FIG. 1;

FIG. 5 is a left side elevational view of the coordinate measuring machine of FIG. 1;

FIG. 6 is a rear elevational view of the coordinate measuring machine of FIG. 1; and,

FIG. 7 is a perspective view of a second embodiment of a coordinate measuring machine of the claimed design.

The ornamental design which is claimed is shown in solid lines in the drawings. The broken lines in the drawings are for illustrative purposes only and form no part of the claimed design.
